UNITED STATES PATENT OFFICE

149,902

DESIGN FOR A GARMENT HANGER

Byron T. Petty, Effingham, Ill.

Application July 11, 1947, Serial No. 140,218

Term of patent 14 years

(Cl. D80—8)

To all whom it may concern:

Be it known that I, Byron T. Petty, residing at Effingham, in the county of Effingham, State of Illinois, have invented a new, original, and ornamental Design for a Garment Hanger, of which the following is a specification, reference being had to the accompanying drawings, forming a part thereof, in which:

Fig. 1 is a perspective view of a garment hanger showing my new design, and

Fig. 2 is an elevation of the opposite side thereof.

I claim:

The ornamental design for a garment hanger, as shown.

BYRON T. PETTY.
